METHOD OF AND APPARATUS FOR EVACUATING OIL WELLS

Filed Nov. 17, 1928

UNITED STATES PATENT OFFICE

LOUIS W. SOUTHGATE, OF WASHINGTON, DISTRICT OF COLUMBIA

METHOD OF AND APPARATUS FOR EVACUATING OIL WELLS

Application filed November 17, 1928. Serial No. 320,203.

In patent granted to me October 2nd, 1928, No. 1,686,475, I have described and shown a method of and apparatus for causing oil to flow through pipe lines, which consists in employing a suction pump to suck the oil along in a section of the pipe line, in removing the gas and utilizing the same, if desired, and in then forcing the oil along on its next journey by a pressure pump.

In the present improvement, I plan to apply this method and apparatus directly to the top of one or more oil wells. By doing this, several important advantages are obtained. First, the pumping or lift in the well is assisted by the suction effect, and second, the gas which comes along with the oil, or which is evolved as the oil is pumped up in the well can be separated from the oil and salvaged and utilized.

When an oil well is driven and comes in, the gas first released is very often saved and utilized, as it is very rich in hydro-carbons. This initial flow generally is limited.

After this flow of gas is over, unless the well is a gusher, it is the practice to pump the oil up out of the well, usually with pistons reciprocated in the well casing, the pumping very often being done from great depths.

As this pumping goes on, considerably more gas may be drawn from the ground, or may be evolved by the churning action of the pumping mechanism, and this gas thus drawn along or evolved during the pumping usually has been allowed to go to waste.

By the application previously described, this gas can be saved and utilized.

To accomplish these desirable ends, I close the top of the well casing with a stuffing box through which the piston rod for reciprocating the pistons of the lift pump will work, and I connect the pumping apparatus shown in my patent to the top of the oil well.

The connections to the pumping apparatus may extend directly from the casing of the oil well, or the separating tank, illustrated in my prior patent may be employed.

Thus the pumping action in the well will be helped to a degree, depending upon the vacuum generated by the applied apparatus, and the oil pump thereof may be employed

to force the oil along on its journey from the well; and at the same time the gas as it comes up in the well or is evolved intermittently or continuously may be collected and utilized.

The apparatus and connections are illustrated in diagram or outline in the accompanying drawings, in which—

Fig. 1 illustrates a lay-out in which the connections extend directly from the oil well, and

Fig. 2 illustrates a lay-out in which a separating tank is employed.

Referring first to Fig. 1, in detail, W designates an oil well in which is arranged a suitable pumping apparatus, which may comprise pistons P—P and check valve C, coordinated so that by reciprocating the pistons, the oil will be lifted up in the well casing.

The top of the well casing is extended above the ground and is closed by a stuffing box S—through which the pump piston or rod works.

A pumping mechanism M, which may be constructed in accordance with Fig. 2, of my prior patent, is arranged at a suitable location and is driven by a suitable motor. This pumping mechanism consists of a liquid centrifugal pump having one or more impellers I and a hydro-turbine gas pump H employing the oil for its pumping action. The well casing is connected near its top by a pipe 10 to the gas pump and is connected at a lower level by pipe 11 to the liquid or oil pump.

The gas pump H is connected to suck the gas or air from the top of the well casing and force the same through a pipe 12 to any suitable storage place, as a gasometer G, from which the salvaged gas may be led and utilized.

A blow-off can be arranged at a low point on the gasometer to allow any air or heavy non-inflammable gas to escape as very often air comes up in the well or leaks into the apparatus.

The oil pump I—I is connected to force the oil along on its journey from the oil well, by a pipe 13, which may be the first section of a pipe line.

It is not thought necessary to illustrate the pumping mechanism in greater detail, as the same is fully shown in my prior patent and the exact apparatus there shown may be employed.

By the combination and connections described, the pumping action in the well will be assisted and the gas which comes along up in the well with the oil or which is evolved by the churning action of the pump pistons will be separated out and can be utilized.

In Fig. 2, I have shown a modification in which a pipe 15 extends from the oil well to a separating tank B similar to the separating tank B of my prior patent. This separating tank may be advantageously employed in locations where a large quantity of oil is to be handled or where the apparatus is applied to a plurality of wells, it being obvious, of course, that a plurality of wells can be piped together, so that one pumping apparatus will handle the combined output thereof.

The pumps and mechanisms herein described have been selected as the best elements now known by me for practicing the invention, and I fully appreciate that other kinds of pumps may be employed.

The details and arrangements herein shown and described may be greatly varied by a skilled mechanic without departing from the scope of my invention as expressed in the claims.

Having thus described my invention, what I claim as new and desire to secure by Letters Patent of the United States, is:—

1. The method of evacuating an oil well which consists in first lifting fluids comprising oil and gas therein by pumping, then separating the gas from the oil, and assisting the lift of fluids by the application of suction applied to the fluids at a point beyond the point of separation.

2. The method of evacuating an oil well which consists in first lifting fluids comprising oil and gas therein by pumping, then separating the gas from the oil, and assisting the lift of fluids by the independent application of suction to the gas and to the oil.

3. The method of evacuating an oil well which comprises in first lifting fluids comprising oil and gas therein by pumping, then separating the gas from the oil, and assisting the lift of fluids by the simultaneous independent application of suction to the gas and to the oil.

4. The method of evacuating an oil well, which consists in pumping oil from the well, in separating the gas which comes along with the oil, or which is evolved by the churning action of the pumping from the well during such pumping, and permanently removing such gas.

5. The method of evacuating an oil well, which consists in pumping oil from the well, in separating the gas which comes along with

the oil, or which is evolved by the churning action of the pumping from the well during such pumping, and permanently removing such gas, and applying suction to the lifted oil thereby to assist the pumping action of the well.

6. The method of evacuating an oil well which consists in lifting fluids comprising oil and gas therein by pumping and by the additional application of suction to said fluids, and then separating the gas from the oil and in removing the gas and oil independently of each other for subsequent utilization.

7. The method of causing fluids to flow from an oil well which consists in applying pressure to the fluids at one point in the well, separating the fluids from each other and applying suction to the separated fluids at another point in the well, permanently removing the gaseous fluids from the oil and then forcing the oil along on its journey.

8. The method of causing fluids to flow from an oil well, which consists in applying pressure to the fluids at one point in the well, separating the fluids from each other and applying suction to the separate fluids at a point adjacent the well, permanently removing the gaseous fluids from the oil and then forcing the oil along on its journey.

9. The combination of an oil well, a pumping mechanism therein for lifting fluids in the well, including gas and oil in the well, means for separating the oil and gas, and means to independently apply suction to the gas and oil respectively whereby the lift in the well is assisted and the gas is removed for subsequent utilization.

10. The combination of an oil well, a pumping mechanism therein for lifting fluids in the well, including gas and oil in the well, means for separating the oil and gas, and means to simultaneously independently apply suction to the gas and oil respectively, whereby the lift in the well is assisted and the gas is removed for subsequent utilization.

11. The combination of an oil well, a pumping mechanism therein for lifting fluids in the well, means including a gas suction pump connected to the well to assist the pumping action in the well by application of suction to fluids therein and to handle the gas raised in the well.

12. The combination of an oil well, a pumping mechanism therein for lifting fluids in the well, a gas pump and an oil pump connected to the well to assist the pumping action by the independent application of suction to the fluids thereby to separate the gas from the oil and separately remove the gas and oil for subsequent utilization.

13. The combination of an oil well, a pumping mechanism therein for lifting fluids in the well, a gas pump and an oil pump connected to the well to assist the pumping action by suction, to separate and handle the

gas and to force the oil and gas respectively forward from the well.

14. The combination of an oil well, a pumping mechanism therein for lifting the oil, a separating tank, a gas pump and an oil pump respectively connected to the well to assist the pumping action therein by suction, to separate and handle the gas and to force the oil forward on its journey from the well, said 10 gas and oil pumps being effective to handle the gas and oil independently of each other.

In testimony whereof I have hereunto affixed my signature.
